UNITED STATES PATENT OFFICE.

ALBERT KATZKE, OF ERIE, PENNSYLVANIA, ASSIGNOR OF ONE-HALF TO
JACOB HAMMER, OF ERIE, PENNSYLVANIA.

COLLAPSIBLE BABY-CARRIAGE.

SPECIFICATION forming part of Letters Patent No. 699,186, dated May 6, 1902.

Application filed August 13, 1901. Serial No. 71,885. (No model.)

To all whom it may concern:

Be it known that I, ALBERT KATZKE, a citizen of the United States, residing at Erie, in the county of Erie and State of Pennsylvania, 5 have invented certain new and useful Improvements in Collapsible Baby-Carriages; and I do hereby declare the following to be a full, clear, and exact description of the invention, such as will enable others skilled in 10 the art to which it appertains to make and use the same.

This invention relates to collapsible baby-carriages; and it consists in certain improvements in the construction thereof, as will be 15 hereinafter fully described, and pointed out in the claims.

The object of the invention is to provide a baby-carriage or light vehicle which may be so folded as to be readily handled when collapsed.

The invention is illustrated in the accompanying drawings, as follows:

Figure 1 shows a side elevation of the carriage in position for use. Fig. 2 shows a plan 25 view of the same; Fig. 3, a side elevation of the vehicle collapsed; Fig. 4, a plan view of the same; Figs. 5 and 6, details of the central joint of the axle and locking mechanism therefor.

30 A A mark the main sections of the axle, which are provided with a centrally-located joint a. The outer ends of the axle are connected by the joint a' to an extension A', on which the wheels B are mounted. Extending 35 upwardly from the extension A' A' are the uprights C, and jointed on these uprights are the forwardly-extending frame-pieces D D and the joints c on the uprights C. The stops a² limit the inward movement. Telescoping 40 the frame-pieces D are the extension frame-pieces D', which are connected to the uprights e, extending from the fork E, by means of the joints d. The wheel F is arranged in the fork D in the usual manner. Extending from the 45 upper end of the upright C is the top frame-piece D². This is connected with the upright C by means of the joint c'. It is fixed at its lower end by means of the connection d' with the frame D. It is also provided a short distance above the frame D with a tubular piece 50 d², from which extends the upper extension

frame-piece D³. This upper extension frame-piece D³ is connected with the upright e by means of the joint d³, which allows a return of the upright e. Extending forwardly from 55 the center of the axle is a tubular guide A², and extending into this guide is a rod G. The rod G is rigidly connected at its forward end with the fork E, and when the axle A is brought to position for use the end of the rod 60 G projects through the end of the guide A². The rod is provided with a notch g, which is engaged by a catch g', fastened to a bracket A³ on the axle. (See Figs. 5 and 6.)

The joint a is of the ordinary hinge construction, which permits of the axle being swung toward the rear; but the edges a² a² coming in contact when the axle is in a forward position limit the forward movement to one which brings the parts A A in line.

When it is desired to fold the carriage, the catch g' is removed, the axle swung toward the rear. This brings the wheels to the inner position. (Shown in Fig. 4.) The joint c permits of the wheels being brought into parallel position when they are in their inner position, thus reducing the space which they occupy. The joints d³ and d permit this folding action at the forward end of the triangular frame. The tubular guide A² is of sufficient length 80 to prevent its withdrawal from the rod G. After the parts are folded if desired, they may be slipped back by the sliding extension D' in the frame-piece D and the upper extension D³ through the tubular portion d². 85 The rod G slides through the tubular guide A². It will be noted that the rod G maintains the forward wheel in alignment.

Extending to the rear from the uprights C C is the seat-frame H. This is provided 90 with the joint h, the axis of which is preferably in a horizontal plane, and also the centrally-located joint h'. Extending from the frame adjacent to the joint h' is a rod H', which passes through an eye h³ in a block h², 95 which is jointed by means of the bolt h⁵ on the bracket A³. A set-screw h⁴ is provided for locking the rod H' in position. When the parts are brought to position for use, the rod H' supports the frame H and maintains it in 100 a horizontal plane. The eye h³ is preferably larger than the rod H', so, if desired, the rod

may be run through it as the frame H is folded.

Secured to the frame H any desirable collapsible seat may be attached, preferably of 5 some flexible fabric.

What I claim as new is—

1. In a collapsible baby-carriage, the combination of the axle having the two parts A A, and joints, a a'; a forwardly-extending 10 frame; a rod, G, connected with the forward end of the frame; and means for locking said rod with the axle to lock the axle in its open position.

2. In a collapsible baby-carriage, the combination with the axle having the parts A A, and joint, a; the extensions, A' A' and joints, a'; the forwardly-extending frame jointed on the extension, A' A'; and means connected with the said frame for locking the axle in 20 an open position.

3. In a collapsible baby-carriage, the combination of a jointed axle; a frame narrower at the front than at the rear; a joint between the axle and the frame sides and between 25 said frame sides and the wheel-supporting devices at the front of the carriage; and said wheel-supporting devices.

4. In a collapsible baby-carriage, the combination of the axle, A A, having the joint, 30 a'; a tubular guide, A²; the extensions, A' A'; the uprights, C, on said extension; the upper and lower frame-pieces jointed on the upright; the fork, E; joints between said frame-pieces and the fork, E; and the rod, G, extending from the fork into the tubular guide for locking the axle in an open position.

5. In a collapsible baby-carriage, the combination of a jointed axle; uprights extending from said axle; a seat-frame secured to 40 said uprights having joints with horizontal axes at its connection with the uprights; and a joint having a horizontal axis lengthwise of the carriage in the seat-frame to permit the folding of the seat-frame by a movement 45 of the parts in a downward direction.

6. In a collapsible baby-carriage, the combination of a jointed axle; uprights extending from said axle; a seat-frame secured to said uprights, having joints with horizontal 50 axes at its connection with the uprights; a

joint having a horizontal axis lengthwise of the carriage in the seat-frame to permit the folding of the seat-frame by moving the parts in a downward direction; and means for locking the seat-frame in the upper position.

7. In a collapsible baby-carriage, the combination of a jointed axle; uprights extending from said axle; a seat-frame secured to said uprights having joints with horizontal axes at its connection with the uprights; a 60 joint having a horizontal axis lengthwise of the carriage in the seat-frame to permit the folding of the seat-frame by moving the parts in a downward direction; a rod extending from the seat-frame to the axle; and means 65 for locking said rod with the axle.

8. In a collapsible baby-carriage, the combination of the jointed axle, A A, with the extension, A'; a frame narrower at the front than at the axle; a front fork connected with 70 the forward end of said frame; joints between the fork and the frame and between the axle and the frame; and means for telescoping the frame to contract the length of the vehicle.

9. In a collapsible baby-carriage, the combination of the axle having the parts, A A, with the joints, a; the joints, a' a' and extension, A' A'; the uprights, C C; the frame-pieces, D D, jointed on the uprights, C; the extension frame-pieces, D' D', arranged to 80 telescope the frame-pieces, D; the front fork and joint between the front fork and frame-pieces, D' D'; the upper frame-piece, D², extending from the upright, C, to the frame, D; a joint between said frame-piece and the upright, C; the upper frame-piece, D³; telescoping means between the frame-pieces, D² and D³; the joint, d³, between the frame portion, D³, and the fork; the seat-frame, H, secured to the upper end of the upright, C, and having joints permitting of its folding in a downward direction; and the rod, II', for supporting the seat-frame in an open position.

In testimony whereof I affix my signature in presence of two witnesses.

ALBERT KATZKE.
